MULTITINES RAKING TOOL

Ralph L. Laible, 14408 White Deer Lane,
Omaha, Nebr. 68112

Filed Apr. 16, 1973, Ser. No. 351,178

Term of patent 14 years

Int. Cl. D8—05

U.S. Cl. D8—13

FIG. 1 is a multitines raking tool, showing my new design;

FIG. 2 is a bottom plan view thereof;

FIG. 3 is a side elevational view thereof, and the opposite side is a mirror image of the side disclosed;

FIG. 4 is a rear elevational view thereof; and

FIG. 5 is a front elevational view thereof.

I claim:

The ornamental design for a multitines raking tool, substantially as shown and described.
